(57) **CLAIM**

The ornamental design for a water leak detector, as shown and described.

DESCRIPTION

FIG. 1 is a perspective view of a water leak detector, showing our new design in a first embodiment;

FIG. 2 is a front view of the embodiment shown in FIG. 1; FIG. 3 is a rear view of the embodiment shown in FIG. 1; FIG. 4 is a side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1;

FIG. 8 is a perspective view of a water leak detector, showing our new design in a second embodiment;

FIG. 9 is a front view of the embodiment shown in FIG. 8; FIG. 10 is a rear view of the embodiment shown in FIG. 8; FIG. 11 is a side view of the embodiment shown in FIG. 8; FIG. 12 is another side view of the embodiment shown in FIG. 8;

FIG. 13 is a top view of the embodiment shown in FIG. 8; and,

FIG. 14 is a bottom view of the embodiment shown in FIG. 8.

Broken lines illustrate portions of the water leak detector that form no part of the claimed design.

1 Claim, 10 Drawing Sheets
